UNITED STATES PATENT OFFICE

FRANCIS O. WILLIAMSON, OF ALAMEDA, CALIFORNIA

BALL MILL

Application filed May 21, 1928. Serial No. 279,366.

This invention relates to ball or pebble mills of the type shown in my prior Patent No. 1,413,644 of April 25, 1922, and has for its objects the provision of improved deflecting heads for the mill whereby a more efficient ball movement is obtained, and consequently a superior ground product is produced by the mill in a given length of time or with a given expenditure of horsepower. Also such a deflecting head which is better adapted to compartment mills of the ball type.

Briefly described the invention comprises a cylindrical revolvable mill with deflecting vanes or wedges arranged within on the confronting heads of the mill, similar to those shown in my patent aforesaid with the exception that all, or substantially all elements of the vanes or wedges slant from the periphery of the mill in a direction toward the axis of the cylinder but away from the head to which they are attached or form a part. Or more correctly no part of the wedge shaped developments slant in the reverse direction from that explained above or as shown in my prior patent aforesaid in Figs. 1 and 2 at 9 and 10.

Besides the above it is desirable that all the wedge elements as above first defined shall extend tangentially to a circle around the main axis of the mill or to a cone or cylindrical development therearound, or other figure concentric with the axis.

Further when the deflecting heads are used in cylindrical chambers to form compartment mills, a spaced pair is used to form a material receiving chamber between each two compartments, and certain faces of the wedges are left open in a manner so that material can flow into successive compartments yet preventing the balls from doing so, on account of the direction of rotation of the mill.

In the drawings accompanying this application Fig. 1 is a vertical and longitudinal section through a typical portion of a compartment ball mill constructed in accordance

with my invention, having four deflecting wedges on each head.

Fig. 2 is an isometrical view of the right-hand end of a mill showing six deflecting wedges in position.

Figs. 3, 4, 5, 6 and 7 are reduced size diagrammatic front views of different heads showing various modifications to the tangentially arranged deflecting wedges on the inner surface of the heads.

Figs. 8, 9, 10 and 11 are views showing cross-sections of variously formed deflecting wedges optionally used on the heads.

In further detail the drawings show a mill comprising a cylindrical shell 1 provided with tubular bearing trunnions 2 at opposite ends (one only being shown) supported in self aligning bearings 3 of conventional construction.

Within the cylinder are suitable liner or wearing plates 4 bolted or otherwise held in place and which liner plates are made in relatively small sections so as to be replaceable through a suitable man-hole (not shown) in the cylinder.

The cylindrical shell may be of any diameter or length depending on the requirements of the particular mill, though usually it will be of a length about equal to its diameter if of the single chamber variety, or multiples thereof for the compartment mills.

In the construction shown in Fig. 1 the trunnion bearings 2 are formed integral with the outer head 5 of the cylinder and also with a relatively short piece 6 of the cylindrical shell itself, being joined at 7 by means of bolt flanges to the main body of the shell.

Within the short cylindrical portion 6 of the outer head is positioned one of my improved deflecting heads 8.

This deflecting head 8 is bored about the same internal diameter as the trunnion bearing 2 and a feed tub 9 extends through both members as shown in Fig. 1. The feed tube is preferably of smaller diameter at its outer

end so as to provide a slightly downward incline at its bottom so that material will readily feed therethrough with the mill mounted on a level axis of rotation.

5 Spaced from the inner head 8 and secured in place by any suitable means such as the bolts indicated are two deflecting heads 10, 11 arranged to provide a relatively large hollow space 12 between them, and these heads are also provided with central bores 13—14.

10 Beyond the spaced heads 10, 11 may be a number of similar heads, followed by a head at the other end of the cylinder so as to provide any number of compartments, or for a single compartment mill but two complementary end heads of the kind shown at 8 are used.

15 As stated, the heads are provided with wedge-shaped deflecting surfaces similar to those shown in my prior patent aforesaid with the exception of the development of the planes involved.

20 There may be any number of wedge elements arranged on the heads, four being used in Figs. 1 and 3 to 7, and six in Fig. 2.

25 The wedge elements in the present case each have a long apex A extending from adjacent the inner periphery of the shell to a point of tangency with a circle B concentric with the axis of the mill and at a slight angle in a direction extending toward the opposite end of the mill, or toward the confronting head 10 if in a compartment mill. In the former patent the angle of the apices of the wedges was from the periphery of the mill back toward the head or toward the mill axis but away from the opposite or confronting head, thus differing from the present showing.

30 The apices A of the wedges in Figs. 1, 2, 6 and 7 are shown as straight lines, whereas in Fig. 3 as convex curves tangential to the circle B, in Fig. 4 concave, and in Fig. 5 as an OG curve.

35 The plane or ball deflecting surface C of the wedge elements may be arched, OG, or straight as shown respectively in Figs. 8 to 10, and the termination of the wedge element or base thereof may be substantially at right angles with the plane of the head as shown at D in Figs. 1, 2, 8 and 9 or it may be less abrupt as shown at E in Fig. 10, or concavely curved as shown at F in Fig. 11, and in any of the modifications the base joins the next wedge plane C on a base line G also extending from the periphery of the head toward the axis of the mill and toward the opposite end or confronting head of the mill, while terminating tangentially with respect to circle B.

40 It has been found after exhaustive experiments that a ball mill provided with confronting deflecting heads complimentarily formed along the principles of design above explained and revolved in direction of the arrows of Figs. 1 and 2 will effect great economy

in time of grinding as well as overcome the excessive wear on the deflecting surfaces found with the old style heads. This is thought due to the combination of angular and tangential development of the surfaces 70 C which results in a constant falling away of these surfaces behind the mass of balls being lifted in rotation of the mill, combined with the greater percussive action of the balls upon leaving the said surfaces.

75 While I show in Fig. 2 the inner ends of both lines A and G meeting at the same point against the circle B, this may be varied within reasonable limits by decreasing the angle of line G at the hub of the head and then more or less abruptly curving out to meet line A.

80 In the showing of Fig. 1 intermediate head 10 is provided on the surface of the deflectors with small perforations in the form of slits 15 for the passage of ground material to the space 12 between the intermediate heads 10 and 11 and from which space the ground material automatically discharges to the next compartment of the mill to the left of head 11 upon rotation of the mill for further grinding by balls or pebbles therein, and thence to still another compartment if desired, or to finally discharge therefrom, if the latter be the last compartment.

85 The discharge of the ground material from the intermediate head space 12 is effected through openings in the D walls of the head, or omission of said walls in head 11. These openings are hard to understand in Fig. 1 though they are indicated at 16, and to further clarify the construction a dotted line 16' is drawn on the isometrical view Fig. 2 of head 90 8' as it is similar in other respects to head 11.

95 It should be understood that I show the deflecting head 8 as a separate part for ease of manufacture and replacement, but if desired the wedge elements may be cast directly on the main cylinder head 5.

100 It should also be understood that while I show the inner ends of the wedge elements extending tangent to a circle B, they may be tangent to any other figure arranged around the main axis of the mill.

110 In operation the mill compartment or compartments are charged with various size grinding balls or pebbles and material to be ground substantially to the dotted line 17, the mass banking up towards the center of each compartment as indicated at 17' owing to the action of the deflecting surfaces C. In intermediate space 12 the ground material 18 received through slits 15, due to the interior surfaces of the deflecting wedges and direction of rotation of the mill, is continually discharged to the following compartment, and at the same time any of the grinding balls from the second compartment which may back up into space 12 will roll out.

115 The peculiar arrangement of the angular deflecting surfaces herein shown, for the 125

reasons already stated, has been found to result in a much longer life to the wedge elements besides giving the grinding balls a combination of rolling or grinding action followed by a better impact action toward the center of the mill than possible to obtain in the earlier construction.

While I show the deflecting heads as made of one piece castings, this is for simplification of the drawing only, as it is manifest they may be made in any number of parts bolted to the members 5 and 6. Also it should be noted that the special form of end or outer head members 5 including a deep ring 6 parted from the main shell 1 at 7 constitutes new construction providing for removal of the body of the mill by slight axial separation of the end bearings 3.

It is of course understood without showing in the drawings that any form of gear or other drive for the mill is to be incorporated in the construction.

I claim:

1. In a mill of the character described, a revolvable shell, heads on said shell, deflecting wedges arranged on the confronting faces of said heads, said wedges including a series of main surfaces extending from the periphery of the head in a direction generally away from the head and towards the axis of the mill and developed on lines terminating tangentially to a figure around said axis at a point furthest removed axially from the respective head upon which the wedges are arranged.

2. In a mill of the character described, a revolvable shell, heads on said shell, deflecting wedges arranged on the confronting faces of said heads, said wedges including a series of main surfaces extending from the periphery of the head generally towards the axis of the mill and towards the confronting head.

3. In a mill of the character described, a cylindrical shell, heads on said shell, means by which said shell is mounted for revolution on a horizontal axis extending longitudinally of the cylinder, a series of wedge-shaped deflecting elements within the shell arranged against the heads in confronting relation, said elements provided with working surfaces extending generally towards the axis of the mill and towards the confronting series of deflecting elements.

4. In a mill of the character described, a cylindrical shell, heads on said shell, and an intermediate head forming compartments in said shell, said intermediate head provided with an interior space and a series of similar wedge-shaped deflecting elements on opposite outer sides formed with openings whereby ground material will pass from one compartment of the mill to the other.

5. In a mill of the character described, a cylindrical shell, heads on said shell, said heads formed with a cylindrical return shell

portion flanged and removably bolted to the shell by bolts extending longitudinally of the shell.

6. In a mill of the character described, a cylindrical shell, heads on said shell, said heads formed with a cylindrical return shell portion outwardly flanged and removably bolted to the shell by bolts extending longitudinally of the shell, and a series of wedge-shaped deflecting elements mounted on said heads within said return portion.
